US00D718736S

(12) **United States Design Patent**
Thompson et al.

(10) **Patent No.:** US D718,736 S
(45) **Date of Patent:** ** Dec. 2, 2014

(54) **AUDIO PLAYER AND SPEAKER SYSTEM**

(75) Inventors: **Katie Thompson**, River Falls, WI (US);
Andrew Cottrell, Minneapolis, MN (US);
Rick Kogler, Forest Lake, MN (US)

D607,283 S * 1/2010 Mahan et al. D7/606
D610,569 S 2/2010 Fiebel et al.

(Continued)

(73) Assignee: **Imation Corp.**, Oakdale, MN (US)

OTHER PUBLICATIONS

(**) Term: **14 Years**

Filing Receipt for U.S. Appl. No. 61/569,806, filed Dec. 13, 2011.

(21) Appl. No.: **29/410,493**

(Continued)

(22) Filed: **Jan. 9, 2012**

Primary Examiner — Keli L Hill

(51) **LOC (10) Cl.** 14-03

(74) **Attorney, Agent, or Firm** — Dorsey & Whitney LLP

(52) **U.S. Cl.**

(57) **CLAIM**

USPC D14/196; D14/168; D14/212; D14/215

The ornamental design for an audio player and speaker system, as shown.

(58) **Field of Classification Search**

USPC D14/137, 155, 162, 167-172, 188, 189, D14/193-198, 203.1-203.8, 204, 207, 208, D14/209.1, 210-217, 257, 258, 265, 299, D14/496; 181/143, 144, 147, 148, 150, 153, 181/157, 198, 199; 381/300-303, 306, 332, 381/333, 336, 345, 361-364, 386-388; 369/6-12; 455/90.1-90.3, 344-355

See application file for complete search history.

FIG. 1 is a perspective view of an audio player and speaker system;

FIG. 2 is a front view of the audio player and speaker system of FIG. 1;

FIG. 3 is a rear view of the audio player and speaker system of FIG. 1;

FIG. 4 is a right side view of the audio player and speaker system of FIG. 1;

FIG. 5 is a left side view of the audio player and speaker system of FIG. 1;

FIG. 6 is a top view of the audio player and speaker system of FIG. 1; and,

FIG. 7 is a bottom view of the audio player and speaker system of FIG. 1.

The broken lines shown are included for the purpose of illustrating the unclaimed portions of the article and form no part of the claim.

1 Claim, 7 Drawing Sheets
